Primary Examiner — Keli L Hill(74) *Attorney, Agent, or Firm* — Kenja IP Law PC(57) **CLAIM**

The ornamental design for a portable radio, as shown and described.

DESCRIPTION

FIG. 1 is a front perspective view of a portable radio showing my new design;

FIG. 2 is a rear perspective view thereof;

FIG. 3 is a front view thereof;

FIG. 4 is a top view thereof;

FIG. 5 is a right side view thereof;

FIG. 6 is a left side thereof;

FIG. 7 is a rear view thereof; and,

FIG. 8 is a bottom view thereof.

The broken lines shown are included for the purpose of illustrating portions of the portable radio that form no part of the claim.

1 Claim, 8 Drawing Sheets(56)
